UNITED STATES PATENT OFFICE.

VOJTECH PUC, OF PRAGUE-VINOHRADY, BOHEMIA.

SAFETY PIN.

1,415,473.

Specification of Letters Patent.

Patented May 9, 1922.

Application filed August 4, 1919. Serial No. 315,112.

(GRANTED UNDER THE PROVISIONS OF THE ACT OF MARCH 3, 1921, 41 STAT. L. 1313.)

To all whom it may concern:

Be it known that I, VOJTECH Puc, a citizen of the Czech-Slovak Republic, residing in Prague-Vinoohrady, Bohemia, have 5 invented certain new and useful Improvements in Safety Pins, (for which I have filed applications in Austria, filed April 15, 1915, patented September 13, 1916, No. 72,915, in Czech-Slovakia, filed July 3, 1919, 10 patented March 20, 1920, No. 814,) of which the following is a specification.

This invention relates to safety pins made for the most part of wire and provided with a guard for the pointed end of the pin, 15 and the object of the invention is to provide means whereby the pointed end of the pin may be freed from its guard without manipulating that part of the pin which contains its point.

20 The invention further consists in so forming the pin as to make it possible to open it with one hand or with two fingers while the other hand of the user may be otherwise engaged.

25 The invention also consists in forming a pin of the kind referred to in such manner that it may serve as a hanger for goods fixed to the pin or as a label holder for various kinds of goods.

30 In the accompanying drawings:—

Figure 1 is a perspective view of a safety pin embodying my improvements, showing the pin closed.

35 Figure 2 is a similar view, showing the pin about to be opened. The pin is made entirely of two pieces of metal, namely, the wire part which forms the pointed member A, the spring B and the laterally projecting member C, hereinafter more partic-

40 ularly described, while the guard D is made of a single piece of sheet metal and may be of usual form, having a slotted opening d of any suitable shape. One end of the wire is anchored at x in the guard, while the

45 pointed member is free to bend and move into and out of the guard. The laterally projecting member C is produced by causing the wire to overlap at e in substantially the same plane, producing parallel portions as

50 shown. The ends of these portions are then bent downwardly, as indicated at e to produce two substantially parallel parts f although preferably these parts are slightly

inclined. The two parts f are then bent at their outer portions g and then turned inwardly and formed into a coiled spring h. The parts last described constitute a laterally projecting member which forms a handle for the pin and by means of which the pin can be opened with one hand. It also provides a hanger inasmuch as the pin may be attached to a garment, goods of various kinds, or labels or advertisements. The hanger may be supported on any suitable device.

When the pin thus constructed is employed to suspend goods, the laterally projecting member C will of course be arranged uppermost. The spring of the laterally projecting member C is under such tension 70 that it normally holds the pointed end of the pin in the guard, but if the opposite side members be grasped by the hand or by the thumb and first finger and pressed towards each other the base of the safety pin or those parts between the bends e will be moved outwards, thus lengthening the base and moving the guard longitudinally away from the spring B so that finally the point of the pin will spring out of the guard, in the manner indicated in Fig. 2, where it will be observed that the members f have been pressed towards each other, the distance between the bends e has been lessened and the point is just about to leave the guard. A slight 85 additional pressure on the parts f will cause the point to leave the guard. When pressure on the parts f is relieved, the parts between e, e assume their normal position and then the pointed end of the pin may be made 90 to engage the guard in the usual way.

I claim as my invention:

1. A safety pin provided with a laterally projecting member and having parts which are movable under spring tension to 95 lengthen the pin as a whole and to thus withdraw the pointed end of the pin from its guard.

2. A safety pin, comprising a pointed member, a guard with which it co-operates, 100 a spring for the pointed member, a part of the pin permanently attached to the guard, and a laterally projecting member interposed between the guard and the spring for the point which has parts movable relatively 105 to each other under spring tension to move

the guard laterally away from the spring for the point and thus release the point from the guard.

3. A safety pin, comprising a guard made 5 of sheet metal and another portion made entirely of wire, comprising a pointed member, a coiled spring at the end of the pin for the pointed member, a laterally projecting member connected on one side to the guard and 10 on the opposite side to the spring, having a coiled spring at its outer end and overlapping portions at its inner end.

4. A safety pin provided with a pointed member, a looped end, and a guard, the loop being connected with the guard by a member provided with a laterally projecting portion comprising two parts having overlapping portions at their inner ends and having their outer ends cross-connected for the purpose specified.

15 In testimony whereof, I have hereunto
20 subscribed my name.

VOJTECH PUC.
